UNITED STATES PATENT OFFICE.

JOSEPH H. MILLER OF HARRISBURG, TEXAS.

DISPENSING CAN.

Application filed July 23, 1926. Serial No. 124,336.

This invention relates to improvements in dispensing cans and is particularly directed to certain improvements on the dispensing can shown in U. S. Patent 1,570,270 granted 5 to me January 19th, 1926.

The novelty in the present improved structure resides in certain features in the nozzle and the stem whereby to provide a more substantial guide for the stem; to enable the 10 cap-end of the stem to be swung laterally out of alinement with the discharge-end of the nozzle so that the contents may be poured from the nozzle without hindrance by the cap and to enable the cap and stem to be 15 more readily operated to remove or replace the cap and to permit the inner end of the stem to be operated in the container so as to serve as an agitator.

With these, and other objects in view, the 20 invention is illustrated in the accompanying drawing, wherein,—

Fig. 1 shows the complete can in side elevation.

Fig. 2 illustrates the nozzle and the upper 25 portion of the can in longitudinal section and shows the stem with its loop-end tilted as necessary when entering the same in or withdrawing it from the can-end.

Fig. 3 shows the can and nozzle in longitudinal section with the stem moved out and the outer end of the stem swung laterally to move the cap out of position in front of the 30 nozzle.

Fig. 4 illustrates a cross-sectional detail 35 through the nozzle and stem, the section being taken on the line 4—4 of Fig. 3.

Fig. 5 shows another cross-sectional detail 40 through the nozzle and the stem,—the section being taken on the line 5—5 of Fig. 3, and

Fig. 6 illustrates the outer end of the nozzle with the locking notches therein.

Referring to the structure shown in the drawing, the numeral 10, designates the cylindrical body of the container, which in this instance is presumed to be a sheet metal 45 can.

The head-end 11 of this can has a breast 50 12, with a central nipple 13 and this nipple is exteriorly threaded at 14 with coarse threads and has a central opening 15 therein. A flat ledge 16 is formed on the nipple about the opening 15 for a purpose that will presently be explained.

55 With the container or can, I provide a spout or nozzle 17 containing novel features.

This nozzle 17 is slightly tapered, being larger at its base or attaching-end than at its discharge-end, and at said attaching end, the nozzle has an internal cap structure comprising a crosswise partition 18 with a series of perforations 19 therein and a central opening 20.

The internal cap structure also has an annular screw-threaded flange 21 which engages the threads 14 on the nipple 13.

The cap structure is permanently soldered or otherwise attached to the lower end of the nozzle and is thus a permanent part 70 of the latter.

A sealing gasket 22 is seated in the internal cap structure at the under side of the partition 18 and this gasket seats on the edge 16 of the nipple and forms a tight joint between the cap and nipple when the nozzle is 75 attached.

At the smaller discharge-end 23 of the nozzle, I provide a central guide-tube 24, which depends in the nozzle and this tube is carried by a cross-bar 25, which has its opposite ends 26 turned down in and permanently fastened to the inside of the nozzle-tube.

The central guide-tube 24 is in axial alignment with the central opening 20 in the partition 18 and a stem 27 extends through the nozzle,—passing through the guide-tube 24 and also through the opening 20 in the cap-partition.

The stem 27 is formed of wire and has a 90 flat or elongated loop 28 at the inner end beyond the internal cap structure.

The form and construction of this loop 28, is precisely like that disclosed in my said prior patent and no claim is made herein to 95 this loop in itself, but briefly, the loop is formed with one side 29 extending laterally a greater distance from the stem 27 than the other side 30 so that it becomes necessary to turn the loop to a precise position 100 to enter it in the nipple-opening 15 or to remove it from that opening, precisely as explained in my said patent.

Between the partition 18 of the cap-structure and the inner end of the central guide-tube 24, I provide the stem 27 with a cross-plate 31 having flat sides 32, which provide passages 33 in the nozzle for the inlet of air and the outlet of fluid during the pouring or dispensing operation and at two 110 opposite sides this friction cross-plate 31 has rounded edges 34 which latter, when

the stem is drawn out to its limit, will lie close to the inner wall of the nozzle.

The stem has an outer end portion 35, which is pivotally connected at 36 to the 5 stem proper and this outer end portion extends through a flanged cap 37 which is shaped to snugly fit the outer end 23 of the nozzle. The cap 37 is permanently attached to the outer end portion 35 of the stem and 10 an eye or loop 38 is provided on the outer end of said stem portion to enable the latter to be readily grasped by the hand to draw the stem outwardly.

By reference to Figs. 2-3 and 6 of the 15 drawing, it will be noted that the outer end 23 of the nozzle is provided with a plurality of edge-notches 39 and that when the stem has been pulled out until the pivot end 36 is projected from the tubular guide 24, 20 the outer end 35 of the stem may be swung laterally and seated on one of the edge notches 39 in which said end will be held and thus prevent the stem from rotating or from moving back into the nozzle.

25 The lateral displacement of the cap 37 by swinging the stem end 35 also removes the cap from in front of the discharge-end 23 of the nozzle so that when dispensing dressing on traveling belts, the nozzle may 30 be held close to the belt and the dressing properly distributed thereover.

During the dispensing operation, air may enter the nozzle and pass inwardly through one of the passages 33 while the dressing 35 will flow through the other of said passages 33 in a flat ribbon form and be delivered at the nozzle-end.

As all the parts are connected, loss of any of them will be avoided,—it being unnecessary to entirely disconnect the stem from the can even to refill the latter.

Having described my invention, I claim,—

1. In a dispensing can the combination with a can-body having a nozzle-engaging connection, of a nozzle detachably connecting with said body-connection, a stem extending through the nozzle said stem having a pivoted outer end portion to enable said portion to be swung laterally when drawn outwardly from the nozzle and a cap attached to the outer pivoted end of the stem and shaped to cover the nozzle end.

2. In a dispensing can the combination with a cylindric body having a projection at one end thereof said projection being provided with an opening, of a tapered nozzle detachably connected to the projection,—said nozzle having guide-means therein and also having notches in its outer smaller rim-edge, a stem extending all the way through the nozzle and guided by said guide-means therein said stem having a pivoted outer end portion and a cap attached to the pivoted outer end portion of the stem and shaped to fit the smaller end 65 of the nozzle said pivoted end portion of the stem when drawn outwardly from the nozzle to unseat the cap being movable laterally to seat in the rim-edge notch of the nozzle and hold the cap out of alinement 70 with the nozzle-end.

In testimony whereof I affix my signature.

JOSEPH H. MILLER.
